UNITED STATES PATENT OFFICE.

CHESTER A. SCOTT, OF STOCKTON, CALIFORNIA.

GRADE ATTACHMENT FOR TRANSITS.

1,105,930.

Specification of Letters Patent.

Patented Aug. 4, 1914.

Application filed May 9, 1912. Serial No. 696,120.

To all whom it may concern:

Be it known that I, CHESTER A. SCOTT, a citizen of the United States, residing at Stockton, in the county of San Joaquin, State of California, have invented certain new and useful Improvements in Grade Attachments for Transits; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in transits used for surveying and engineering purposes, the object of the invention being to produce an attachment for ordinary transits used for leveling purposes which will provide a means, formed as a component part of the instrument, for contour and grading purposes.

The invention further embodies certain means for attaching the grade and contour telescope and its frame to the frame of the level transit. Such grade and contour attachment has certain lever attachments for the purpose of operating and adjusting the same which are coöperatively disposed upon its frame.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings similar characters of reference indicate corresponding parts in the several views.

Figure 1 is a side elevation of the level transit showing the grade and contour attachment mounted thereon. Fig. 2 is a side elevation of the grade and contour attachment. Fig. 3 is a sectional view of the adjustment mechanism for the grade and contour attachment.

Referring now more particularly to the characters of reference on the drawings, the numeral 1 designates the supporting base for the level transit, while the numeral 2

designates the side supporting frames therefor and the numeral 3 designates the telescope disposed in said frames 2.

In applying my improved invention, I first provide a hub member 4 having an end flange 5, such member 4 being provided with a threaded recess 6 adapted to screw onto the end of the spindle of the telescope 3. Mounted completely over the hub 4 is a sleeve 7 formed as a component part of which is a platform 8 having an upwardly projecting threaded pin 9.

The numeral 10 designates a supporting frame having a sleeve 11 screw mounted on the pin 9 in which frame 10 is pivotally mounted the grade or contour telescope 12. Mounted on the outer end of the spindle of the telescope 12 is a tangent arm 13 having adjustable pins 14 adapted to impinge against a lug 15 on the frame 10, such adjustment pins being of the usual type used for such adjustment and one of them being provided with a thumb screw 16 for this purpose. On the lower end of the sleeve 7 and formed as a component part thereof is a 180 degree arc 17 movable over a vernier 18 secured to a steady brace 19 having a collar 20 disposed over the sleeve 7, such steady brace 19 being secured at its lower end by means of adjustment screws 21 adapted to impinge against the frames 2. Mounted on the sleeve 7 is another collar 22 formed as a component part of which are tangent arms 23 having adjustment screws or pins 24 impinging against a lug 25 on the steady brace 19. A set screw 26 projects through the collar 22 and is adapted to engage the sleeve 7 when desired for a purpose as will appear.

Projecting from the hub 4 is a threaded pin 27 screw mounted on which is a cap 28 having a flange 29 adapted to abut against the member 22 to hold said members 22, 20 and 7 against the flange 5. When in this position as shown in Fig. 3, the cap 28 is then at the ends of the threads on the pin 27 and thereafter any further turning movement of the cap 28 will also turn the hub 4 for the purpose of screwing the same upon the spindle of the telescope 3 for the purpose of fixing the same upon said spindle or for adjustment purposes as may be desired. A spring 30 is interposed between the cap 28 and the member 22 to maintain the said parts in a steady position.

In operating my improved attachment, the arc 17 may be turned to any desired point, the same, and the vernier 18 being provided with any suitable designations to indicate the different points desired (this designation not being shown for the reason that it is old and well known in the art). The position of the telescope 12 would then be changed accordingly for the reason that it 10 is a component part of said arc 17, as described. The said telescope 12 and its frame in practice would be provided with the usual balancing structure commonly used with telescopes of this character and no showing of 15 the same has been made in this specification as the same forms no part of my invention. After the arc 17 has been turned and a finer adjustment is desired, then the set screw 26 is operated to impinge against the collar 7 20 which then forms the members 22 and 23 as a fixed part with respect to said sleeve 7. Then by the movement of the adjustment screws 24, the members 23 and 22 and incidentally the sleeve 27 and its connected telescope 12 may be adjusted with exactness to 25 any desired position. Then a still finer adjustment of the telescope 12 may be had by the operation of the threaded screw 16 which moves the tangent arms 13 one way 30 or the other, as desired, and incidentally moves the telescope 12 for the reason that the arms 13 are mounted on the spindle of said telescope 12, as described.

The steady brace 19 as will be seen holds 35 the vernier steady under all conditions and can be adjusted to any desired position by means of the set screws or pins 21.

From the foregoing description it can be 40 readily seen that I have designed such an attachment as may be applied to the spindle of the telescope of any transit, which attachment can be used for different purposes than the transit and especially for grade and contour work as set forth herein. It will be 45 especially noted that I have shown none of the scaling or indicating points or numerals commonly used on instruments of this kind as the same could be of any desired type and I do not claim the same as a necessary combination for my improved mechanical attachment.

While this specification sets forth in detail the present and preferred construction of the device, still in practice such deviations from such detail may be resorted to 50

as do not form a departure from the spirit of the invention.

Having thus described my invention what I claim as new and useful and desire to secure by Letters Patent is:

1. A device of the character described comprising the combination with a transit, of an attachment adapted to be mounted on said transit, such attachment comprising a hub, a sleeve mounted on said hub, a telescope carrying frame mounted on said sleeve, an arc mounted on said sleeve, and means for adjusting the position of said sleeve on said hub, as described. 60

2. A device of the character described comprising the combination with a transit, of an attachment adapted to be mounted on said transit, such attachment comprising a hub, a sleeve mounted on said hub, a telescope carrying frame mounted on said sleeve, a steady bar mounted on said sleeve, a tangent lever mounted on said sleeve, means for holding said members in position on said sleeve, and means for adjusting the position of said sleeve by the operation of 75 said tangent lever, as described. 80

3. A device of the character described comprising the combination with a transit, of an attachment adapted to be mounted on said transit, such attachment comprising a hub, a sleeve mounted on said hub, a telescope carrying frame on said sleeve, a tangent lever having a collar mounted on said sleeve, and a set screw disposed through said collar and adapted to impinge against said 85 sleeve, as described. 90

4. A device of the character described comprising the combination with a transit, of an attachment adapted to be mounted on said transit, such attachment comprising a hub, a sleeve mounted on said hub, a collar mounted on said sleeve, a steady bar on said collar, another collar mounted on said sleeve, a tangent lever disposed on said second named collar, means for fixing said second 95 named collar stationary with respect to said sleeve, and a cap screw mounted on the end 100 of said hub and adapted to hold said collars in position on said sleeve, as described.

In testimony whereof I affix my signature 105 in presence of two witnesses.

CHESTER A. SCOTT.
